William Ward Davidson, Evanston, Ill., assignor
to Davidson Manufacturing Corporation, a cor-
poration of Illinois

Application August 11, 1941, Serial No. 406,328

12 Claims. (Cl. 101—217)

The subject matter of this invention is a two-purpose duplicator capable of doing both direct and offset printing. For direct printing, the raised type, or so-called "letterpress" process, is ordinarily used; and for offset printing, the lithographic process is preferred.

Most, if not all, duplicators on the market before this invention were one-purpose machines. They could do either letterpress printing, directly from a raised type plate to the sheet being printed, or they could do offset lithographic work in which the positive image on the lithographic plate is first transferred to a rubber blanket and then to the sheet being printed. They cannot, however, do both direct and offset printing.

The offset lithographic process is rapidly displacing direct letterpress printing for reasons unimportant here, but there are some printing jobs which, by reason of inherent limitations in the lithographic process, or because of cost, are almost necessarily performed by the letterpress process. Printing just a few words in a blank left in previously printed pamphlets, cartons, and the like is one such instance. This is called "imprinting."

Large printing shops can afford to have both lithographic presses and letterpress machines, but there is a large demand in smaller printing establishments, and in stores, manufacturing plants, business houses, and the like, for a single, relatively small, moderately priced duplicator capable of doing quality printing by either the letterpress or lithographic processes.

A two-purpose duplicator designed for and used largely in this specialized field will, in most instances, be operated by persons skilled only slightly, if at all, in the printing field, and hence one of the paramount objects of the invention is to so organize, construct, and arrange the essential elements and mechanisms of the machine that it is characterized by simplicity, ease of adjustment, convenience of operation, and the speed by which it can be converted from a direct printing letterpress machine to an offset lithographic machine, and vice versa.

To achieve the broad objects of a two-purpose machine, the conventional employment of three printing cylinders is discarded, and, instead, only two cylinders are used, one being larger than the other and preferably having a diameter that is twice that of the smaller cylinder. The larger cylinder or drum is provided with removable plate and platen segments, while the smaller drum carries a blanket. When the machine is used

for lithographic offset printing, a plate is mounted on the plate segment, and during one-half the revolution of the large drum the image is transferred to the blanket, and during the next half revolution of the large drum the blanket transfers the image to the sheet being printed.

To convert the machine into a direct printing letterpress duplicator, the platen segment is removed, and in its place a direct printing letterpress segment is substituted. The plate segment is removed from the machine and, if a hard platen surface is required, it may be substituted for the blanket, or a steel cylinder may be substituted for the blanket cylinder. The dampening mechanism used when the machine is doing lithographic printing is constructed so that it is self-contained and may be removed from the machine with little effort. The entire conversion from lithographic printing to letterpress printing can be accomplished within the space of a very few minutes.

Provision is made so that the head margin for the printed sheet may be accurately determined, whether the duplicator be set for letterpress printing or lithographic printing. To this end, the two segments carried by the large drum are made angularly adjustable, and means are provided so that their position with respect to a fixed point on the drum may be accurately determined.

Another outstanding feature of this invention is the manner in which the sheets are fed to the bite of the printing rolls, registered with reference to the printing plate, and then delivered onto a pile with the printed side of the sheet facing up, regardless of whether the machine is doing letterpress printing or lithographic printing. Advantage is taken of the fact that the larger drum is exactly twice the size of the smaller drum, and a chain delivery is used employing but a single gripper bar which grips the sheet prior to the time that the sheet reaches the bite of the printing cylinders and carries it through the bite, stripping it from the ink-carrying transfer surface and finally delivering it to the catcher with the printed side of the sheet facing upwardly, where it may readily be viewed by the machine operator. This positive handling of the sheet by a single set of grippers as the sheet passes through the bite of the cylinders results in extremely accurate registration and dispenses with the usual set of grippers carried by one of the printing cylinders.

2. The throwout mechanism for automatically separating the printing cylinders whenever a

sheet fails to reach the bite at the prescribed time is another novel feature of this invention. It is so constructed that it is quiet in operation and is characterized by its relative simplicity. A counter is associated with the throwout mechanism to count the sheets that are actually printed, but the counter is so arranged that the check for the presence of the sheet is completed before the sheet reaches the bite of the printing cylinders.

Provision is made for adjusting the parallelism between the two printing cylinders, and a simple micrometric or slow-motion adjustment permits the printing pressure to be accurately determined. The machine is sturdily built and, once these adjustments are made, will hold them over long periods of time.

The ink mechanism is constructed to effectively break up the ink and distribute it evenly over the printing plate. A novel ductor cutout makes it easier to avoid excess inking when the machine is running without supplying sheets and to clean up the rollers when the machine is being shut down. The vibrator distributing roll is reciprocated in the usual manner but with novel and simplified mechanism for effecting the longitudinal movement of the roll.

For the most part, the drives for all moving parts of the machine are taken from the shaft of the larger drum, thereby facilitating manufacturing assembly and adjustment of the timing for the machine.

Considered as a whole, the machine is outstanding for its ability to perform quality printing by either the direct or offset methods, and many other objects and advantages will become apparent as the disclosure proceeds and a detailed description of the various parts of the machine is made with reference to the accompanying drawings, in which:

Figs. 1A and 1B are diagrammatic views of the press and conveyor table, respectively, arranged for offset lithographic printing.

Figs. 1C and 1D are diagrammatic views of the press and conveyor table, respectively, arranged for direct letterpress printing.

Fig. 10B is a vertical sectional view through the dampening unit, taken approximately on the irregular line 10B—10B of Fig. 10A.

Fig. 10C is a vertical sectional view taken approximately on the line 10C—10C of Fig. 10A.

Fig. 10D is a fragmentary detail view showing a preferred manner of securing the removable dampening unit in proper position.

Fig. 11A is a fragmentary sectional view taken diametrically through the main cylinder and illustrating particularly the means of securing the plate and platen segments thereto.

Figs. 11B and 11C are enlarged fragmentary cross-sectional views showing the bite between the platen segment and the blanket roll, Fig. 11B showing the shims which are used between the platen sheet and the platen segment when a thin paper is being printed, and Fig. 11C showing the same parts without the shims when a thick paper is being printed.

Fig. 11D is a fragmentary sectional view showing the interior of the main cylinder, the view being taken approximately on the line 11D—11D of Fig. 11A.

Fig. 12A is a chart illustrating the timing of the movement of the various parts of the press and showing the position of each part at any given angular position of the main cylinder, the zero position being the position which it is in when the blanket and plate first come together.

The parts are not in the same positions in all of the figures.

At the outset, it should be understood that the invention may be embodied in many forms, but a preferred embodiment has been illustrated in the drawings and will hereinafter be described in detail.

Before considering the detailed structure of the machine, it will be helpful to refer, first, to the diagrammatic illustrations shown in Figs. 1A to 1D.

In Fig. 1A, the machine is shown set up for offset lithographic work, and in Fig. 1C the machine is shown set up for direct letterpress work. By considering the progress of a sheet of paper through each arrangement of the press and the timed relationship of the various parts of the machine as they cooperate in applying the image to the sheet, it will be easier to understand the detailed description that follows.

GENERAL ORGANIZATION

A. Lithographic offset printing (Fig. 1A)

Sheet A in Fig. 1A has just been printed, and sheet B is about to be lifted by the suction head of a feeder C, an intermediate sheet already being on a diagonal tape conveyor board D. Upon reaching the rotatable stop fingers E, sheet B may be jogged against a side guide, against which it is also urged by the diagonal tape, to assure proper later position. At the same time, or shortly thereafter, a feeler finger F is moved toward the bite of the printing rolls to check that the sheet is in proper position. If for any reason the sheet is not there, the finger F will drop through a slot in the feed board and actuate an arm G, which functions to separate the printing rolls; but, if a sheet is present, it prevents the feeler finger F from dropping into the slot and the printing rolls are held in cooperative relationship. The same movement of the feeler finger F also operates a counter if a sheet is present. Otherwise, the counter is not actuated.

After the sheet has been brought into end registry with the stop fingers E and has been properly positioned laterally, as the feeler finger F makes its check, the upper of feed rolls H descends upon the sheet, grips it while the rolls are still stationary, and then cooperates with the lower feed roll to move the sheet toward the bite of the cylinders while the stop finger E is rotated out of the way.

During this process of bringing sheet B to the bite of the printing cylinders, the upper or larger cylinder I, which carries a plate J on one peripheral segment and a platen surface on another peripheral segment K, has been rotating to ink up the plate J, and apply the image to the blanket L carried on the smaller or lower cylinder M, where it is ready to be applied to the sheet when it reaches the bite of the printing cylinders. As will be seen by reference to Fig. 1A, the water form roller 216 of the dampening unit N applies the dampening liquid to the plate J, and then the ink form rollers of the inking unit O apply ink to the plate image. While sheet A is being carried to catcher P by gripper Q of the chain delivery mechanism and sheet B is being positioned by stop fingers E, plate J applies its lithographic image to the blanket L. On the next half revolution of the large drum I, the gripper Q, actuated by a cam R, releases the sheet A after turning it upside down around the drum-like assembly S, and thereupon proceeds around the blanket drum M to a position where it is again opened by a cam T to receive sheet B as it is fed forwardly toward the bite of the cylinders. The gripper Q then closes and grips the sheet to carry it through the bite, while the feed rollers H, which have been traveling at a peripheral speed slightly above the peripheral speed of the printing cylinders in order to insure proper registration of the sheet within the gripper Q, releases the sheet and the gripper carries the sheet through the bite and thence around the drum-like assembly S, where it is released into the catcher.

A suitable cam is provided along the margin of the platen segment K to lift the water form roller and the ink form rollers from the platen when it passes beneath these rollers, and it should be noted that during the period that the platen K is passing under the inking mechanism O the rollers of this mechanism are continually rotating to break up the ink and replenish the ink on

the ink form rollers for the next application of ink to the printing plate.

B. Letterpress printing (Fig. 1C)

5 For direct printing, the platen segment K would be replaced by a direct printing element which in the illustrated form shown in Fig. 1C is a type-bearing segment U. It will be observed that this is put in the position of the platen rather than in the position of the plate so that it will co-act with the smaller lower cylinder at the time a sheet is fed thereto. In this instance the lower cylinder serves as a platen. In some instances its blanket may be used as a platen surface and in other instances it may be desirable to remove it and apply a harder surface.

When a typographic printing member, such as type segment U is used, no dampening is necessary and hence the dampening unit N of Fig. 1A 10 may be omitted. The plate J will also be omitted and, if the segment bearing it is not also removed, the ink form rollers will be completely out of contact with this segment but will be allowed to 15 come into contact with the type on the type segment U, which will then print directly on the upper surface of the sheet.

Since the upper surface of the sheet is printed, it is desirable to deliver the sheet to the collector P' without turning it over, so that the sheet may 20 be inspected. To this end a special cam V is provided, as seen in Fig. 1C, which opens the gripper Q approximately at the position thereof shown in Fig. 1C or shortly before reaching this position. An ejector roller W is provided to cooperate 25 with the drum-like wheels S to insure continued movement of the sheet A' so that it is delivered into the collecting box P' or other suitable receiver. Of course, the collecting box P' may be the same collecting box as that shown at 30 P in Fig. 1A moved to a new position.

A modified form of the press for direct printing should also be mentioned. According to this form, the press will print two sheets for each revolution of the large cylinder, or, in other 35 words, one sheet for each revolution of the small cylinder. This is accomplished by providing a direct printing plate or the like on each segment of the main cylinder I, and modifying the feed and delivery mechanism to feed and deliver a sheet of paper for each plate. Thus, the blanket L would serve only as a platen or could be replaced by a platen. A second gripping unit would be provided in the chain delivery unit midway of the length of the chains from the gripping unit Q. The cams at the margins of the plates would cause both plates to be inked and, if they were lithographic plates, to be dampened before inking. As each plate approached the platen roll M, a sheet would be fed to one of the grippers and carried by it to the bite where it would be printed by said plate. The sheets could be delivered to the same receptacle or to two different receptacles.

C. Combined offset and direct printing, front and back

With the form of the press illustrated, both the front and the back faces of a sheet could be printed simultaneously by a special arrangement. 40 For this purpose the offset plate J would be left in place and the platen segment K would be replaced by a segment bearing a direct-printing lithographic plate. The plate J would be a positive plate so that it would produce a negative image on the blanket L, which in turn would

print a positive image on the underface of the sheet. The plate in place of the segment K would have a negative image thereon so that it would print a positive image on the upper face of the sheet at the same time that the blanket prints the lower face thereof. Thus, the negative plate in place of the platen K would serve as the platen for the blanket L, while the blanket would simultaneously serve as the platen for the negative plate. It should be observed that no change is necessary in the feeding or delivery for this arrangement. Of course, the dampening and inking form rollers would be permitted to contact both plates.

DETAILED DESCRIPTION

From the foregoing description of the general organization of the press, it is believed that the general operation of the press will be sufficiently clear so that a detailed description of the various parts may be readily understood.

PARTS B TO D—PRELIMINARY FEEDING

The sheets may be separated from one another by any desirable sheet separator. That which is partially illustrated is a suction feeder of a type which has been manufactured heretofore by the Davidson Manufacturing Corporation. The sheets are lifted up one by one by a suction nozzle 11 and fed to pull-out rolls 12, the lower of which is constantly driven and the upper of which is accurately positioned with respect to the lower roll by thumb nut 13. A detector may be provided for automatically deflecting the sheets from their normal course if more than one is fed at a time.

The entire sheet-separating unit C is controlled by linkage 16 driven from a crank pin 17 rotating rigidly with printing cylinder I so as to ensure accurate timing of the preliminary feed of the sheets with respect to the movement of the press. In the form of feeder illustrated, the feeder includes pile mechanism for automatically raising the pile of sheets B so that the top sheet thereof will always be at a level suitable for engagement by the nozzle 11.

The pull-out rolls 12 pass the sheet on to a conveyor table D which may comprise a belt or belts 21 and one or more preliminary rolls 22. Suitable traction means, such as marbles 23, may be provided for pressing the sheet against the rolls and the belt.

Reversible bias

For various reasons it is sometimes highly desirable to position a sheet by two particular edges, say the top edge of the sheet and the right-hand edge of the printed side of the sheet. If the upper face of the sheet is being printed, the positioning of a side guide 26 at the right-hand side of the conveyor table D will be correct and the sheet may be pressed against this side guide either by biasing (slanting) the tapes toward the side guide or by providing a jogger for engaging the far side of the sheet to press the sheet against the side guide, or both. However, it will be observed that if the underface of the sheet is being printed, the edge of the sheet which is the right-hand edge of the top face of the sheet is the left-hand edge of the bottom face of the sheet and would be the left-hand edge of the printed sheet. Accordingly, in order to permit lateral registration by the right-hand edge of the underface of the sheet, it is preferred that the side registration means be reversible. To this

end the table D may have incorporated therein the reversible bias features disclosed in my Patent No. 2,190,413, the tape carrying and driving rolls 21 being shiftable about approximately vertical axes along the longitudinal center line of the table, and the belts being shiftable thereon so as to bias the sheet, either to the right as shown in Fig. 1B or to the left as shown in Fig. 1D. The side guide 26 is preferably interchangeable between the two sides of the machine.

Instead of relying on a biased conveyor table D, a jogger may be used for pressing against one side edge of the sheet, preferably pressing it against a side guide on the other side of the sheet. If it is desired to have the jogger optionally effective in either direction, this may be accomplished by having a single jogger reversible on a rod and providing means for changing the timing of the reciprocation of the rod so that at the proper time it can be made to jog the sheet in either direction. Of course, the side guide could be shiftable to either side as in the case of the side guide 28 of Figs. 1B and 1D. Of course, a press may have both reversible bias and reversible jogging.

PARTS E TO H—FINAL FEEDING

The parts E to H and their control may be substantially the same as those illustrated in my prior Patent No. 2,246,508. Preferably they are all controlled by cams rotating rigidly with one of the printing rolls so that utmost accuracy of timing is ensured. As seen best in Fig. 4A, the pressure roll 30 (of feed rolls H) is raised by cam 31 operating through lever 32, an angle bar 33, which may be considered as a shaft, being pivoted at 35. The angular position of the cam 31 with respect to the other control parts is such that while the pressure roll 30 is raised, a sheet will be fed under it against stop fingers E. The stop fingers E are carried by shaft 34 which also has feed roller 36 rigid thereto, as seen best in Fig. 2A.

The shaft 34 and with it the stop fingers E and the feed roller 36 are jointly driven as seen best in Fig. 6A. The shaft 34 carries a pinion 37 which is driven by a gear segment 38 carried by a pivoted lever 39, the follower roller 40 of which is urged against cam 41 by spring 42 compressed along slide rod 43.

As cam 41 rotates, it will swing lever 39 and gear segment 38 downwardly, rotating stop fingers E and feed roller 36 in an advancing direction. The shape of the cam 41 is such as to accelerate the sheet smoothly and rapidly so that, before the grippers Q close upon the sheet, the sheet will have reached a speed slightly in excess of the speed of the grippers Q so that the sheet will be buckled slightly against the registration stops of the grippers Q.

After the grippers have closed on the sheet, the cam 31 raises pressure roller 30 so that the sheet may be drawn freely by the grippers. After raising of the pressure roller 30, cam 41 rotates to a point where it permits spring 42 to push the gear segment 38 upwardly, rotating the stop fingers E and feed roller 36 back to the starting position in time for the next sheet to be fed against the stop fingers E.

70

PARTS I TO K—LARGE CYLINDER

The construction of the large cylinder I is probably seen best in Figs. 3A, 5A, and 11A to 11D. The end walls of the cylinder are formed by discs 46 which are rigidly mounted on a shaft 47 jour-

naled (with ball bearings) in the press frame. Platen K and plate holder 48 for plate J comprise segments which are suitably secured to the discs 46 spanning the space between them, and are provided with suitable stiffening ribs, as clearly shown in the drawings.

The preferred securing means for the segments is seen best in Figs. 11A and 11D. A socket screw 51 countersunk into the plate holder 48 passes through a slot 52 in the rim 53 of each disc 46 and screws into a nut 54. As seen by comparing Figs. 11A and 11D, the nut is especially shaped to conform to the inner face of rim 53 and is elongated so that it can easily be prevented from turning by engagement with a shoulder 55 at the side thereof. A plate 56 is preferably secured to the rim 53 and provided with a flange 57 to retain the nut in place before the screw 51 is screwed into it, or while the plate holder 48 and the screw 51 are removed. A pin 58 is provided in the nut 54 to facilitate shifting the nut circumferentially along the rim 53 to position it for alignment with the screw 51 as the latter is about to be inserted.

The elongated slot 52 permits shifting the plate holder 48 with the plate thereon circumferentially of the discs 46 for the purpose of adjusting the head margin on the sheet being printed. It is merely necessary to loosen the two screws 51, one for each disc 46, and the segment 48 may be slid the length of the slot 52. When the segment 48 has been moved to its new position so that the head margin on the printed sheet will be correct, the two screws 51 are again tightened and the segment 48 is firmly in place.

As shown at the top of Fig. 11A, the platen K may be secured by a countersunk bolt 61 passing through the platen K and screwing directly into rim 53. However, when the platen is replaced by a type-holding plate, it is desirable to be able to adjust the plate for head margin adjustment as has been described with respect to plate holder 48. For that reason it will ordinarily be preferred that the adjustable securing means illustrated at the bottom of Fig. 11A be also used at the top of Fig. 11A for the platen and for the type-holding plate which replaces it.

Segment lock

In order to facilitate adjusting the segment 48 (or the type segment) for head margin adjustment, a lock arm 63 (Fig. 4A) is pivoted to a bracket 64 carried by crossbar 359 of the main frame and is provided with a pin 65, which, as shown in dotted lines in Fig. 4A, may be inserted in a hole 66 provided in segment 48 for the purpose. With the lock pin 65 thus in place, the segment is held against turning so that the head margin adjustment may be made simply by turning one of the handles 67 which turn the press. The handles 67 are rigidly mounted on a shaft 68 on which is also rigidly mounted a pinion 69 which meshes with lower cylinder gear 71.

It may be noted, incidentally, that the shaft 68 is part of the main drive for the press, being driven by motor driven belt 72 which extends along pulley 73 on shaft 68.

Head margin calibrations

Adjustment of the head margin may also be facilitated by providing calibrations 76 (Fig. 8B) on one of the discs 46, which calibrations may be visible through a cutout 77 in the edge of plate holder 48.

Shims

With a two-cylinder press in which the large cylinder carries both the plate and the platen, there is a serious problem in providing proper pressures for both of these members. When the plate prints onto the blanket, there is no paper between them, and, when the blanket prints onto the paper on the platen, a different pressure may be desired and furthermore the sheet of paper may be of one thickness in one job and of a very different thickness in another job. Accordingly, some provision must be made for obtaining the correct pressures under the varying conditions. Furthermore, the peripheral speeds of the plate surface and the blanket surface must be the same to avoid minute smears, called gear marks, in printing on the blanket, and the peripheral speed of the blanket surface and the sheet surface being printed must be the same to avoid like smears or gear marks in printing the paper.

As described hereinafter, the axes are normally positioned at the correct distance apart to provide the desired pressure on the blanket.

25. As seen best in Figs. 11B and 11C, the correct pressure for printing the paper A is obtained, without disturbing the optimum spacing of the axes for the blanket, by providing shims 81 between the platen K and a platen sheet 82. Although only two shims have been shown, there are preferably several shims of a variety of thicknesses so that shims may be removed corresponding to the thickness of any sheet being printed. Thus, with a thin sheet of paper A the shims removed may be equal to its thickness, and with a thick sheet A² being printed the shims removed may be equal to its thickness. In this way the total thickness of the sheet of paper being printed, the platen sheet 82 and any shims being used will always be a predetermined thickness. The printing pressure will of course depend not only on the thickness of the sheet being printed and the sheets 81 and 82 but also on the resiliency and the thickness of the blanket L and of course the spacing of the platen K from the blanket holder 84. However, with a given blanket and with a correct spacing of the platen K from the blanket holder 84 to give the correct pressure in printing the image on the blanket, and with the correctly chosen complete set of shims 81, it will merely be necessary to remove the correct shims to match the thickness of any paper being run, and correct printing pressure for the paper will thus be assured. For most purposes a few shims will be enough, since approximation is all that is required.

PARTS L TO M—SMALL CYLINDER

60. As seen in Fig. 3A, the small lower cylinder M may be cast in one piece, that is, with its peripheral portion 86, end portions 87 and hub flanges 88 integral. The hubs 88 may be provided with bearing sleeves 89, which run on bearing portions 91 of a shaft 92. The shaft 92 may be provided with trunnions 93 and 94 eccentric to the bearing portions 91, and journaled in bushings 96 and 97, which are rigidly secured to the main frame except for adjustability of bushing 96, described hereinafter.

65. As will be evident from Fig. 7A, a slight rotation of the shaft 92 about the axis of trunnions 93 and 94 will shift the cylinder M toward or from the upper cylinder I. The shaft 92 is held 75 at a given angular position by a collar 98 rigid

therewith, and seen best in Fig. 3A, which in turn is normally rigidly secured to latch disc 99, which in turn normally bears against pivoted latch arm 101 (Fig. 7A), which is normally held in latching position by means described below.

Pressure adjustment

During printing the latch disc 99 is held in the position shown in Fig. 7A. The angular position of the shaft 92, and hence the spacing of the cylinders I and M, may therefore be adjusted by shifting collar 98 with respect to latch disc 99. This may be accomplished manually after loosening screws 103, which normally hold them locked together. It is preferred that a screw 104 be provided for facilitating a micrometric adjustment between the latch disc 99 and the collar 98 for determining the pressure of the plate J on the blanket L with utmost accuracy. As previously mentioned, the pressure of the blanket L on the printed sheet is determined by shims 81.

Uniformity of pressure along the line of contact may be obtained by loosening screw 106 (Fig. 3A) and turning bushing 96. Screw 106 passes through a slot in the flange of bushing 96. The bore in 96, in which the trunnion 93 is journaled, is eccentric with the outer surface of the bushing 96, so that rotation of the bushing 96 will move one end of the shaft 92 toward or from the large cylinder I, thus producing a uniform pressure irrespective of manufacturing variations.

AUTOMATIC CYLINDER THROWOUT

When a sheet approaches the stop fingers E it slides on top of a table 111 (Figs. 2A and 7A) comprising a sheet of metal. This table is provided with a cut-out slot 112. A detector or feeler 113 is reciprocated along this slot, and is pivotally mounted and so weighted that its leading end 114 will drop into the slot if no sheet is present, but will be supported by the sheet if one is present.

If no sheet is present and the reciprocating feeler 113 drops into the slot 112, it will, upon its movement in the direction of the moving sheet, engage and actuate an arm 116 mounted on a shaft 117. The shaft 117 is normally urged by a spring 118 toward the position shown in Figs. 2A and 7A, with arm 116 resting against cross bar 119. When actuated by the feeler 113 the shaft turns a pin 121 thereon to the right (counter-clockwise), thus putting tension on spring 122 to urge the latch arm 101 downwardly. Normally spring 118, in urging shaft 117 to its normal position, acts through it to urge pin 121 against shoulder 123 of fitting 124 by which latch arm 101 is carried, thus urging the latch arm into the engaging position shown in Figs. 2A and 7A. The fitting 124 is pivotally carried by a fixed sleeve 126, which also forms a bearing for shaft 117. The sleeve 126 is carried by the main frame and is provided with a slot 127 for receiving the pin 121. The pin 121 in turn holds the fitting 124 on the sleeve 126.

It is evident that the feeler 113 must be driven in synchronism with the press, and with such timing with respect thereto that the feeler 113 will be reciprocated in its feeling direction, forwardly of the direction of sheet movement, while a sheet, if properly fed, is present over the slot 112. To this end the feeler is preferably actuated by a cam on the main cylinder I, and it has been found most convenient to connect it to lever 32 by a link 128 pivoted to lever 32, and adjustably positioned in an eye 128' which is pivoted to a short arm 129' rigid with arm 129. As seen best

in Fig. 2B, the arms 129 and 129' are both rigidly mounted on a sleeve 130. The sleeve 130 pivots freely on shaft 152 carried by the main frame. This control of the feeler through lever 32 has the incidental advantages that the feeler 113 is moved forwardly at a time when it will aid in ensuring firm contact of the sheet against the stop fingers E as the pressure roll 30 is lowered onto the sheet, and the feeler 113 is not moved rearwardly until the sheet has already been gripped by the grippers of the chain delivery unit so that proper registration is ensured.

The instant when the feeler detects the absence of a sheet at the slot 112 is not the proper time for a throwout or the separation of the cylinders, since at this instant the cylinders may still be printed the preceding sheet. Release at the time of detection is prevented by the pressure of latch shoulder 131 on latch arm 101, this pressure resulting from the tension of spring 132 on lever 133 which is pivoted to the main frame at 134. Lever 133 is connected to latch disc 99 by an adjustable link 136.

Just before the proper instant for a throwout movement, a cam 137 on shaft 47 of the large cylinder I acts on cam roller 138 to pivot lever 133 counter-clockwise, as seen in Fig. 7A, and relieve the pressure of latch shoulder 131 on latch arm 101. If the throwout shaft 117 was actuated as a result of the absence of a sheet, the spring 122 will now draw the latch arm down out of its position for engaging the shoulder 131. At this time the reducing portion 139 of cam 137 will reach the cam roller 138 and release the lever 133, so that it will be drawn clockwise by spring 132, thus shifting latch disc 99 in a counter-clockwise direction, and with it the shaft 92. Rotating the shaft 92 in a counter-clockwise direction about its trunnions 93 and 94 will thus cause the lower cylinder M to drop away from the upper cylinder I so that, as the cylinders continue to rotate, there will be no contact between them, and hence no offsetting of ink from the blanket on the cylinder M to the platen on the cylinder I.

The throwout occurs shortly before the platen on cylinder I reaches the line of contact with cylinder M, and, after the platen has passed this line of contact, cam 137 will again act upon cam roller 138 to actuate lever 133, link 136, and latch disc 99 to turn shaft 92 in a clockwise direction to restore cylinder M to its printing position. If in the meantime a sheet has been supplied at the proper time for the ensuing impression, the feeler 113 will have been held out of the slot 112 and the spring 122 will no longer be holding the latch arm 101 down. Instead, the spring 118, acting through shaft 117 and pin 121, will be urging the latch arm 101 upwardly, and as soon as the latch disc 99 has been turned by cam 137 to a latching position the latch 101 will slip up behind the latching shoulder 131, thus holding the parts in the printing position even when the reducing portion 139 of cam 137 would otherwise allow them to shift again to the throwout position.

Silent stop

It will be observed that each time a sheet is missing, spring 132 will cause a sudden movement of lever 133 in a clockwise direction, as the steeply reducing portion 139 of cam 137 passes under roller 138. In inking up the press without starting the sheets, or in like situations, this sudden shifting of lever 133 each revolution would result in a noisy press unless the lever 133 were stopped quietly. According to the present

invention a substantially silent stop has been provided, the nature of which is seen best in Fig. 7A.

A stop roller 141 is rotatably carried by a pin 142, which is secured to link 143, pivoted at 144 to the main frame. Spring 146 urges the link 143 in a counter-clockwise direction, pressing the roller 141 against lever 133. When the high portion of cam 137 suddenly rides out from under the follower roller 138, the lever 133 does not strike a rigid stop but, instead, shifts the stop roller 141, with which it is already in contact, to the left or in a clockwise direction, thus pivoting the link 143 about its axis at 144. The link 143 is of such length that lever 133 is limited to its proper movement and the cam roller 138 does not strike against low point of cam 137. It will be observed that the lever 133 is stopped without having any moving parts strike a fixed part. Hence the throwout operation of the press will be substantially silent.

COUNTER

It is customary to provide a counter 151 for counting the sheets printed. In the illustrated form of the invention this counter is actuated by shaft 152 operating through linkage 153 and spring 154. A return spring, in the counter or elsewhere, urges the parts to the position shown in full lines in Fig. 2A and in dotted lines in Fig. 7A, the return movement being limited by stop screw 161. The shaft 152 is actuated from this position by a crank arm 156. The weight or torque of linkage 153 overbalances that of arm 156 and aids the return spring in urging the return of the parts.

It is very desirable that the counter count only actual sheets printed, not revolutions of the press. This is accomplished in the present invention by having the crank arm 156 actuated by the feeler 113, but actuated by it only when a sheet is present. As shown in Figs. 2A and 7A, feeler 113 is provided with an arm 157, which has a dog 158 at its end. This dog is positioned, when a sheet is present, to strike a dog 159 at the bottom of crank arm 156. In short, when a sheet is present the reciprocation of feeler 113 causes dog 158 to engage dog 159 and turn crank arm 156 and shaft 152 to operate the counter 151 through linkage 153.

When there is no sheet present, the feeler 113 pivots so as to fall into slot 112, and this pivotal movement raises dog 158 so that it passes over dog 159, as shown in Fig. 7B, and thereby avoids actuating the counter mechanism.

From Fig. 7A it will be seen that dogs 158 and 159 have their engaging faces inclined at such an angle that once they have come into engagement the feeler 113 can no longer pivot under influence of its weight with respect to lever 129. The result is that as the lever 129 swings to the position shown in full lines in Fig. 7A, it will raise the feeler 113 to the position in which it is shown in full lines in the same figure. This is advantageous, since it raises the feeler 113 off of the sheet before the forward movement of the feeler 113 ceases, thereby preventing any dragging of the feeler 113 on the sheet. Because of the inclination of the faces of dogs 158 and 159, the dog 159 must come to rest sufficiently far forward of the corresponding resting position of dog 158 so that the feeler 113 may pivot freely as it feels for the presence of a sheet.

It will usually be preferred to have the feeler 113 come to rest on top of the table 111 just to

the right of slot 112 (Fig. 7A) so that as a sheet passes under it it will merely have to tip the feeler by the thickness of the sheet. Accordingly, it is necessary for the dogs to be sufficiently separated so that the feeler 113 can move to the position of slot 112 and still be free to pivot. The position of dog 158 is determined by the adjustment of the nuts on the threaded link 128, the position of link 128 at the time in question being determined by the shape of the cam 31. The position of the dog 159 may be determined by adjusting a stop screw 161 in a bracket 162 mounted on the main frame. The stop screw 161 may be engaged by any convenient member of the linkage 153, under influence of the return spring.

PART N—DAMPENING UNIT

In using the press for direct printing the dampening unit is preferably removed, as seen in Fig. 1C, so as to increase the visibility and accessibility of the parts which are being used. Likewise, in substituting a type-carrying segment for the platen it will usually be most convenient to remove the dampening unit for accessibility if, as in the preferred structure, the dampening unit is readily removable.

As seen best in Figs. 6A and 10C, the dampening unit is provided with a separate frame 171, having notches 172 at the bottom of each side thereof each of which fits on a pin 173 carried by the main frame. The only other means of support is in connection with collars 174, one on each side of the dampening unit at the top thereof, and each of which is rigidly carried by the dampening frame 171. As seen in Fig. 10D a sleeve 176 is threaded through the collar 174 to be adjustable therein, and is locked by a lock nut 177. Sleeve 176 rests on boss 179, and its adjustment of the sleeve 176 accurately determines the position of the dampening unit with respect to the cooperating parts of the main press. A socket screw 178, screwing into boss 179 in the main frame, holds the dampening unit firmly in place.

The dampening unit includes a fountain or fountain pan 181 carried by the frame members, having an upwardly opening tubular mouth 182 into which the neck of a bottle of dampening solution is inserted to maintain the dampening solution, which is mostly water, at a predetermined level in the fountain 181. A fountain roll 183 is carried by the main frame in a manner seen clearly in Fig. 10A, and has its lower portion submerged in the bath in the fountain. At a predetermined period in each cycle a ductor roll 184 is shifted to the position shown, against the fountain roll 183. It is urged to this position by a spring 186, and, except for a short while on the roll 183, is held against distributor roll 187 by cam 188. Cam 188 is rigid on a shaft 189, which also bears rigid thereon a gear 191 meshing with and driven by a pinion 192 (Fig. 6A) rigid on a shaft 193. The shaft 193 is in turn rigid with a gear 194, driven by a gear 195 which meshes with and is driven by gear 196 which rotates with the large cylinder I, and is driven by the lower cylinder gear 71. The gear ratio of gear 191 and pinion 192 is such that shaft 189 and cam 188 rotate once for each revolution of the large cylinder I.

While ductor roll 184 is held against fountain roll 183, the fountain roll is rotated slightly, the exact amount depending on the amount of water or dampening liquid which it is desired to pick up during each cycle of the press. As seen in Fig. 4A, the fountain roll 183 is rotated by means of a

ratchet wheel 201, which in turn is driven by a pawl 202 carried by pivoted lever 203, which is actuated by a second pivoted lever 204 urged in one direction by a spring 206 and actuated in the other direction by a cam 207 rigid on the shaft 189. The relationship between the cams 188 and 207 is preferably such that the entire forward movement of pawl 202 occurs while the ductor roll 184 is at rest on the fountain roll 183. The stroke of the pawl 202 is always of the same length, but the amount that it rotates the fountain roll 183 may be regulated by shifting a shield 208 to hold the pawl 202 out of engagement with the ratchet wheel 201 during any desired portion of the stroke of pawl 202. The shield 208 is pivotally carried by the shaft 209 of the fountain roll, and is held in an adjusted position by a spring detent 211. A handle 212 is provided for moving the shield 208, and, as seen in Fig. 10A, a handle 213 is provided for turning shaft 209 and fountain roll 183 by hand when desired, as to wet it when the press is started.

The distributor roll 187 is mounted on the shaft 193 and driven by it. The distributor roll 187 is in constant rotative engagement with a form roller 216, which is carried between two links 217, seen best in Fig. 4A, pivoted about shaft 193. The links 217, and with them the form roller 216, are urged downwardly, each link by a spring 218, the tension of which may be adjusted by turning collar 218' on screw 220, the collar normally being restrained from turning by a setscrew. The downward movement of each of links 217 is limited by screw 219 bearing against normally stationary cam 221. The cams 221 are rigid with shaft 222, which is preferably provided with a handle 225 for turning it to a position which raises the form roller 216 to an idle position. When the form roller 216 is in the lower position as shown, it may bear against the plate J. Pressure of roller 216 on the plate could be determined by adjustment of screw 219, if it bears against cam 221. It is preferred, however, to have clearance between screw 219 and cam 221, in which case the pressure will be determined by spring 218.

The pressure between form roller 216 and distributor roll 187 may be adjusted by eccentric bushings 223, which are provided with hexagonal heads for adjustment and are normally locked in place with set-screws. A shaft 224, on which form roller 216 rotates, is mounted in the bushings 223, one in each link 217, so that rotation of the bushings will move the shaft toward and from distributor roll 187. The shaft may be drawn out axially for replacement of the form roller.

The form roller shaft 224 also carries a pair of lift-off rollers 226, one adjacent each end of the form roller 216. Each of these rollers engages a cam 227, carried by the platen segment K. These cams raise the dampening form roller 216, and in like manner the ink form rollers, so that neither will touch the platen surface.

Ductor roll 184 and form roller 216 are preferably covered with conventional absorbent material. It has been found desirable to use two absorbent materials on the form roller, the inner material being somewhat less absorbent than the outer and tending to take up excess moisture from the outer to form sort of a reserve reservoir for it. The fountain 181 is preferably formed of or lined with porcelain (preferably white, acid-resistant porcelain) or some other material which will prevent electrolytic action under the influence of the dampening solution.

Once during each cycle of the press the ductor roll 184 is shifted against the fountain roll 183, which rotates a predetermined amount to feed a predetermined amount of water to the absorbent covering on ductor roll 184. The ductor roll 184 then shifts to rest against distributor roll 187, and the three rolls 184, 187 and 216 rotate together to supply the additional moisture to the absorbent covering on roller 216 and spread it evenly therearound. The form roller 216 applies the moisture to the plate J, the non-image portions of which retain a film of this water or dampening solution.

PART O—INKING UNIT

Proper distribution of the ink is one of the most important considerations in designing a press. The ink is carried in an ink fountain 231, seen best in Fig. 5A. The ink fountain roll 232 rotates in contact with the ink in a clockwise direction, as seen in Fig. 5A, and draws a film of ink therefrom, the thickness of the film at various points along the roll being determined by a series of screws 233 which adjustably press a ductor blade 234 toward the fountain roll 232. A ductor roll 237 bears against fountain roll 232 during a portion of each cycle, during which portion the fountain roll 232 is rotated slightly to supply ink to the ductor roll 237. The ductor roll 237 then shifts to pass a new supply of ink to roll 238, from which it is passed to rolls 239 and 241, all of which serve as distributor and break-up rolls, the roll 241 in turn supplying the ink to ink form rollers 242.

Each of the form rollers 242 is mounted on a pair of links 243 and is adjustable with respect thereto, as in the case of the dampening form roller 216, to obtain correct pressure between the form rollers 242 and the roll 241. The links 243 are pivotal on shaft 244 of the roll 241, and each link is adjustable by a screw 246 bearing on a normally stationary cam 247 to control the pressure of the form rollers on the plate or other surface being inked. The cams 247 may be turned by a handle to hold the form rollers out of contact with the surface that they would otherwise ink. Each form roller 242 is provided at each end with a lift-off roller 248, which rides on one of the cams 227 to lift the form rollers away from the platen surface. Cam 247 may have four positions, the 90° position either way from that shown raising one form roll only.

The ink fountain roll 232 is carried by shaft 249, which may be driven by pawl-bearing plate 251 in substantially the same manner as shaft 209 of the dampening unit N, with similar control of the amount it is driven. Plate 251 is, in this instance, driven by a link 252 which in turn is driven by an eccentric 253, which is mounted on stud shaft 254 and rotated thereon by sprocket 256 driven by chain 257 from sprocket 258, which rotates with the large cylinder I.

Distributor roller 241 is preferably a vibrator roll, by which is meant that it oscillates from side to side so as to distribute the ink laterally of the press or lengthwise along the rolls. The manner of accomplishing the oscillation is best explained with reference mainly to the exploded view of Fig. 9C. The shaft 244 is oscillated angularly by a yoke 259, which in turn is oscillated by link 261 (Fig. 4A), which is oscillated by an eccentric 262 rotating with the eccentric 253 already described. The shaft 244 carries rollers 263, each of which rotates on a pin 264 screwed radially into the shaft 244. A sleeve 266 slides

on shaft 244 and is provided with spirally disposed slots 267 in which the rollers 263 ride. The sleeve 266 is prevented from turning by engagement of longitudinal slots 268 therein with blades 269 on a fixed collar 271. As the shaft 244 oscillates angularly, the rollers 263 likewise oscillate angularly in the slots 267, and since the sleeve is restrained from rotation by blades 269 it must, under the influence of rollers 263 in slots 267, oscillate longitudinally of the shaft 244.

As seen best in Fig. 9B, the sleeve 266 is provided with an internal sleeve 272 having an angular flange 273 thereon. Oscillator or vibrator roll 241 is provided with a hub portion 274, having a bearing 276 rigid therewith, which rides on sleeve 272 between flange 273 and sleeve 266. Thus, the roll 241 may rotate on sleeve 272 but must oscillate with the sleeve 266, its oscillation being longitudinal of the rolls and of shaft 244. The roll 241 is driven through gear 275 fast thereon, which is driven in the same manner as gear 194 of roll 187 in the dampening unit.

Ink distributing rolls 239 are idler rolls and may be mounted in a very simple manner. Each roll is carried by a shaft 278. As seen in Fig. 6A, 25 the center shaft 278 slips downwardly in slots 279 at each end of the shaft until the center roll 239 comes to rest on the two side rolls 238. There is no thrust on the shaft 278, and hence no bearings are necessary except that the bracket 281, in which the slot 279 is formed, will keep the roll from gradually shifting longitudinally.

Since there is a lateral thrust on the two side shafts 278, each of them is provided with a bearing block 282 at each end, these blocks sliding in additional slots in the bracket 281 until the rolls 238 come to rest on the oscillator roll 241. With this arrangement all three of the rolls 238 may be removed easily whenever desired, and no adjustment with respect thereto is necessary. Lateral adjustment could be provided for the right-hand roll 239 in Fig. 5A so as to permit regulation of the distribution of its pressure between rolls 238 and 241, but this has not been found necessary, slight play being intentionally left in the mounting. Gear 238 is driven by gears 280 and 283 from gear 275.

The ink rollers in the direct train from ductor roll 237 to either form roller 242 are all of different diameters, and the idler rolls are different from any of these, the relations being other than simple multiples. This, together with the constant driving of the ink rolls, ensures maximum breaking up of the ink. The ductor roll is preferably shifted to the distributor roll 238 at the time which will permit maximum rotation of the rolls before the ink reaches the plate, viz: at such time that the fresh ink being passed from roll to roll will reach the position for application to the plate just after the plate has passed said position. Care must be taken, at least if the vibrator has the same cycle as cylinder I, that its eccentric 262 have such angular position with respect to the cylinder I that the cams 227 raise and lower the form rollers 242 at such times as to avoid piling up of the ink on one side of the press. Apparently the best time for the form rollers to shift is approximately at the end of one stroke of the vibrator roll, so that there will be substantially no lateral movement of the vibrator roll for an extended period after the shift of the form rollers. A possible theory is that the shifting of the form roll has a squeegee action producing a thickened line of ink, in which

case it is necessary to avoid sliding the thickened line of ink predominately in one direction.

CLEANING THE INKING UNIT

5 To clean the inking rolls a clean-up attachment 284 is provided. This attachment is in the nature of a tray having slotted brackets so that it can be slid by hand onto a crossbar or strut 286 (resting also on shaft 254) until its lip 287, 10 in the form of a squeegee, made of an oil-resistant synthetic rubber such as "Duprene," comes in contact with oscillator roll 241. Screws 285, near opposite sides of the tray, are pre-set to limit the squeegee to the proper pressure, and the clearance with the screws removed being too small to allow the metal tray to strike the roll. The clean-up attachment is preferably only half the width of the machine and can be slid back and forth along the bar 286. Cleaning fluid is squirted from an oil can onto the rolls 238 or 239 while the various printing rolls are being driven, so that the cleaning fluid is mixed with the ink thereon. Then the tray 284 is wiped back and forth along the oscillator roll 241, cleaning the softened ink therefrom. The process is repeated until the inking rolls are clean. In the initial stages of the cleaning it is best to clean only about half the length of the rolls at a time so that the driving traction between them will not be lost by diluting the ink over the whole length at once. The half-width tray tends to make this partial cleaning seem natural.

During the cleaning process it is desirable for the ductor roll 237 to be in contact with the roll 238 all the time. In this way the ductor roll will also be cleaned and the feeding of additional ink from the fountain roll will be prevented. This is accomplished in the manner seen best in Figs. 6A and 6B.

40 The ductor roll is normally shifted back and forth by operation of cam 288 on shaft 254. The cam 288 engages cam roller 289 on lever 291, which rocks rock bar 292 by which, as seen in Figs. 4A and 5A, the ductor brackets 293 for carrying ductor roll 237 are mounted. It may be noted at this point that the ductor roll 237 is journaled in slotted bearing blocks 294, which slide between bifurcations on the brackets 293, preferably being held therein by spring clips. The ductor of the dampening unit is mounted in the same way.

55 As seen in Fig. 6A the cam roller 289 is normally urged against the cam 288 by a spring 296, applied to an upper arm of lever 291, which is a bell-crank lever. The far end of the spring engages a pin on a second bell-crank lever 297 which is pivoted to the main frame. During cleaning of the inking rolls, or at any other time when it is desired to avoid the feeding of ink, the lever 291 is flipped counterclockwise to the position shown in Fig. 6B, in which position it is seen that the spring 296 is urging the bell-crank lever 291 in the opposite direction, holding the cam roller 289 off of cam 288 and holding the ductor roll 237 against distributor roll 238. The tension of spring 296 holds the bell-crank control lever 291 in either position to which it is shifted manually. As seen in Fig. 6B, the short arm 298 of the bell-crank lever 291 bears against a bearing boss 299 on the main frame, which boss also serves as a bearing for fountain roll shaft 249. As seen in Fig. 6A, the long arm of lever 291 bears on this boss in the other position.

70 To facilitate cleaning of the ink fountain 231 and the fountain roll 232, the fountain may be

removed by loosening thumb nut 301 and swinging it and its stud 302 downwardly about cross-bar 303, on which they are mounted. With this downward swinging of the stud 302 it swings clear of a forked lug 304, which normally holds the fountain 231 in place. The fountain may then be slipped off of the shaft 249 which it normally engages with its bifurcated forward end.

CHAIN GRIPPERS

The chain delivery feeding unit is constructed generally in accordance with a disclosure made in my copending application Serial No. 324,627. A sprocket 306 is carried at each end of the lower cylinder M, and in the plane of each of these sprockets a second sprocket 307 is positioned, the second sprockets 307 being carried by a shaft 308. Around each pair of radially aligned sprockets 306 and 307 extends a chain 309. The shaft 308 is journaled in bearing blocks 311 which are slideable in suitable brackets 312 on the main frame and may be adjusted therein by nut 313 or screw 314 for tightening the chain.

The chain 309 preferably is just twice as long as the periphery of the sprockets 306, so that the chain makes one cycle for each two revolutions of the sprockets 306, or, in other words, one cycle for each revolution of the larger main cylinder I, and hence one cycle for each impression. A single gripping unit Q is carried by the chain, and since there is a single gripping unit which passes around the lower cylinder M for each impression all of the sheets may be fed to this single gripping unit, and hence this gripping unit may be used for registration of the sheets. With more than one gripping unit there would be variations between the gripping units which would cause difficulties or require special precautions. Of course, the chain construction should be such that the gripping unit will always assume the same position with respect to the cylinder M. The gripping unit is not only provided with gripping fingers 321 but also with an arcuate stop finger 322, against which the sheets are fed. While the sheets are held against the stop finger 322, gripping fingers 321 are lowered to clamp the sheet to a grip bar 323.

As seen in Fig. 8A, the grip bar 323 is carried by one of the chain links at each end thereof. Each of the gripping fingers 321 is urged by an independent spring 324 toward the grip bar 323. The gripping fingers 321 are mounted on shaft 326 which is journaled on the grip bar 323, and each is raised by a pin 325 extending through shaft 326. The pins 325 have lost motion with the gripping fingers 321, so that when the fingers are not being raised by the shaft 326 and pins 325 they may bear with independent pressure on the bar 323. The shaft 326 is normally urged in a gripper-closing direction by the springs 324, and is moved to a gripper opening direction at the proper times by a crank lever 327 keyed to the shaft 326. The crank lever 327 is provided with a cam following roller 328.

As seen best in Fig. 4A, a fixed cam T is positioned to actuate the crank arm 327 to open the gripping unit Q at the proper time for receiving a sheet. The cam T may be carried by the main frame by support members 332, as seen in Fig. 3A.

When the sheet is printed on its upper surface it is released before being carried around the shaft 308 by operation of cam V. As seen best in Fig. 8A, the cam V is slidably carried by a stud 336 mounted on the main frame, and is positioned

thereon by a set-screw 337. The end of cam V remote from stud 336 slides on a second stud 338, but need not be locked thereon. When the top surface of a sheet is being printed, the cam V is shifted to the position shown in dotted lines in Fig. 8A and locked therein by set-screw 337. At other times the cam V is shifted to the position shown in full lines in Fig. 8A, in which position it is inoperative, the actuating arm 327 passing by without contacting it.

When the underside of the sheet is being printed, the sheet is carried around the shaft 308, guide discs 341 being provided on shaft 308. In this instance the gripper Q is opened by a cam R, which is carried by bracket 343 slidably positioned along bar 344 and locked in an adjusted position by thumb screw 346. The bar 344 is carried by the main frame.

A resilient sheet stop 348 is carried by an arm 349 secured to the bottom of bracket 343 so that it moves with the bracket. The sheet stop 348 and cam R are slidably positioned so that they can be moved as near to the sprockets 307 as possible while still causing the sheet to drop properly into collecting box P. For a long sheet it may be necessary for the cam R and sheet stop 348 to be slid to the right to the limit of their movement along bar 344 (Fig. 4A), in order to be sure that the entire sheet is turned over properly before it is dropped into collecting box P. With a short sheet, however, the cam R and sheet stop 348 may be shifted to the left so as to release and stop the sheet as soon as it has been drawn sufficiently far around the sprockets 307 so that the sheets will drop into the collecting box P near the bottom thereof for most satisfactory stacking and for maximum visibility.

When the upper surface of the sheet is printed, the collecting box will be positioned as seen at P' in Fig. 1C. As previously mentioned, the cam V will be shifted to its position shown in dotted lines in Fig. 8A so as to open the gripping unit Q at this point. In order to ensure proper continued movement of the sheet a pair of pressure rollers 351 are provided. These rollers are carried by shafts 352, which may be adjustably secured at any desired position in slots 353 in member 354 which is urged downwardly by spring 356, its downward movement being adjustably limited by nuts 357. The member 354, spring 356 and nuts 357 are carried by bracket 358 slidably secured on cross-bar 359, and preferably removable therefrom.

The pressure rollers 351 will each be aligned with a guide disc 341 when the upper surface of the sheet is being printed, so as to provide good traction on the sheet for ejecting it into the collecting box P'. The shafts 352 may comprise a nut and bolt, and may be positioned at such a point that the sheets will be ejected most satisfactorily into the collecting box P'.

Preferably these discs 341 and rollers 351 will be positioned laterally to engage the sheet along the side margins so that there will be no possibility of smearing the ink. When sheets are being printed on the under surface, the rollers 351 may be removed or slid beyond the edges of the sheet, and the guide discs 341 may be moved sufficiently far in from the edges of the sheet to keep the sheet from cupping. Although three guide discs 341 have been illustrated, two will often be enough, and in fact in the present commercial size of press only two are supplied. As seen in Fig. 5A, the guide discs 341 are notched at 361 to receive the gripper unit Q. The discs

341 are slidably keyed on the shaft 308 so that, even though slid from side to side, they will always be synchronized properly to receive the gripping unit Q and so that their peripheral speed will be the same as that of the sheet to eliminate any danger of smearing.

DIRECT PRINTING SEGMENT

Inasmuch as the gripping unit Q and the feeding mechanism are all synchronized to print a sheet as the platen segment K runs in contact with the lower cylinder M, the simplest way to provide direct printing is to substitute the direct printing segment U, which for convenience may be called a type segment, for the platen segment K rather than for the plate J. If the platen segment is secured by stationary bolts or socket screws 61, the type segment being substituted therefor may be secured by the same bolts. However, since circumferential adjustment will be desirable to make adjustments for head margin, it is preferred that the mounting shown for plate holding segment 48 be used for the type segment, whether or not it is used for the platen segment K. As a matter of fact, since the plate holding segment 48 is ordinarily removed from the machine for direct printing, the special nuts 54 may be shifted to the diametrically opposite side of the cylinder and inserted under a plate, like the plate 56, for holding the type segment.

It will be understood, of course, that the type segment U may be a rail segment for the insertion of loose type, or it may be a smooth surface segment for the application of rubber type or metal plates. If either metal type or metal plates are to be used, the blanket L should be removed and another impression surface substituted therefor, preferably a blanket of a somewhat harder rubber and of slightly less thickness so that the printing pressure will be correct in spite of the decreased resilience of the blanket. Calibrations and a cutout for viewing them should be provided for the type segment, as in the case of calibrations 76 and cutout 77 of Fig. 8B for the plate holder 48.

By making the radius of the platen K small enough, and making shims 81 of a correspondingly greater total thickness, raised-image means such as a rubber plate may be used by removing the shims and platen sheet and securing the raised-image means to the platen segment, as by cementing it.

CAMS

It will be observed that all of the cams controlling the registration feeding and the printing of the sheets, except those controlling the chain-carried grippers, are either mounted directly on the larger cylinder I or its shaft so as to rotate directly with this cylinder, or are driven from the cylinder or its shaft. This arrangement facilitates adjusting the cams in the proper timed relationship to one another.

Referring to Fig. 3A, the cam at the extreme right-hand side of the figure is the cam 131, seen also in Figs. 7A and 2A. This is the cam that operates lever 133 to bring the cylinders into printing relationship after a throwout. By loosening screws 366 which secure it to a collar 367 fixed on shaft 47, the cam may easily be adjusted so that it will hold the cylinders positioned in printing relationship only when the gap 368 between the plate and the platen is at the position of contact between cylinders I and M. This timing of the bringing together of the cylinders I

and M is very advantageous because, when a sheet is skipped the plate does not again apply ink to the blanket, and hence the next sheet printed will be printed with the same high quality as if one had not been skipped. Furthermore, in inking up before the sheets are fed, the press may be run as long as may be desired without over-inking the blanket. Of course, this timing can be obtained without adjustability.

10 Looking from right to left in Fig. 3A, the control member next after the cam 131 is sprocket 258 which, as already explained, particularly with reference to Fig. 4A, controls the inking unit in accurately timed relationship to the cylinders I and M. The eccentric 253 on the driven shaft 254 is positioned, and may be adjustably positioned, so as to actuate the ink fountain roll only when the ductor roll 237 is in contact therewith. The cam 288 on shaft 254 is positioned, and may be adjustably positioned, to so time the movement of ductor roll 237 that when it is shifted against the first distributor roll 238 the ink being passed from one roll to the other will reach the line of contact between the right-hand form roller 242 in Fig. 5A and the plate, just after the plate has passed said form roller. This will give the maximum time for breaking up the ink by rotation of the inking rollers before the ink is applied to the plate on the next cycle. In other words, the shortest path the ink must follow from the ductor roll to the plate should be slightly longer than the length of plate, which, at the time the ductor roll is shifted to the distributor rolls, must still pass the line of contact at which said ink will first reach the plate. It may be noted, incidentally, that because of the fact that the various printing rolls are made of different sizes, as well as because of the oscillation of the oscillator roll 241 and the length of rotating time provided while the platen and the two gaps between it and the plate are passing under the inking unit, the ink is broken up with exceptional thoroughness and distributed with exceptional uniformity.

45 Again, following from right to left in Fig. 3A, the next cam is the cam 31 which controls the pressure roller 30 and the feeler 113 so as to bring the pressure roller down on the sheet while the sheet is stationary in contact with the stop fingers E, the initial movement being accompanied by a forward movement of the feeler 113, which will aid in making sure the sheet is firmly against the stop fingers E.

The next control element to the left of cam 31 is cam 227, carried by the platen to lift the dampening and inking form rollers so that they will not engage the platen. A similar cam 227 is carried at the other side of the platen.

Immediately to the left of the last-mentioned cam 227 in Fig. 3A is ring gear 196, which is the main drive gear for the upper cylinder I, being driven by the lower cylinder gear 71 which in turn is driven by pinion 69 on shaft 68, as previously described. It may be noted that the lower cylinder gear 71 rotates about a fixed axis, viz.—the axis of the outer surface of bushing 96, and is connected to the lower cylinder M through any suitable form of Oldham coupling 371. This coupling maintains constant angular relationship between the gear 71 and cylinder M, in spite of relative movement between their axes resulting from the throw-out or pressure adjusting movements of the eccentric shaft 92.

To the left of the ring gear 196 in Fig. 3A is

cam 41, which drives lever 38 and its gear segment 38. This cam is positioned, and may be adjustably positioned, to start moving the feed roller 36 and the stop finger E immediately after the pressure roller 30 has been lowered thereon. It may be noted that the shape of the cam is such as to accelerate the sheet smoothly, thrust it into the open gripper Q, and overfeed it sufficiently to slightly buckle the sheet so that it will be pressed reliably against the registration stop fingers 322 of the gripper Q.

At the extreme left end of the shaft 47 in Fig. 3A is a collar 313, which drives the linkage 16 for controlling the primary sheet feeder C to feed sheets at the properly timed relationship with the press.

CLAMPS

Any conventional or suitable clamps may be used for the plate, the blanket and the platen sheets. In each instance a clamp or securing means may be used which best meets the needs of the particular situation.

It is believed that the clamps at present preferred are adequately illustrated in Fig. 5A. The leading edge of the plate is clamped by a clamp block 378, which may easily be tightened and loosened by turning socket screws 371. The illustrated form of the clamp at the trailing edge of the plate is similar to one disclosed in the co-pending application of Frank J. Breman and Edward F. Dell, Ser. No. 275,722. It includes one or more pivotally mounted eccentric clamp members 378, urged toward a clamp bar 379 by spring or springs 381 and jointly released by operation of a handle 382. The clamp is preferably automatic to the extent that, when the plate J is thrust into clamping position, the eccentric members 378 will shift to receive it and will automatically clamp it under influence of springs 381. The clamp, comprising eccentric 378 and clamp bar 379, is mounted on pivoted levers 383, pivoted to the plate-carrying segment and urged in a plate-tightening direction by spring 384.

The platen sheet 82 will almost never need to be removed, and hence its leading edge may be clamped more permanently by a screw-held bar 386. The trailing edge of the platen sheet is preferably provided with perforations inserted over hook-shaped securing lugs 388 carried by a cross-bar 389 mounted on pivoted links 391 which are urged in a sheet-tightening direction by spring 392. The tension on platen sheet 82 may be adjusted by screw 393. To change the shims under platen sheet 82 it is merely necessary to loosen screw 393 and unhook the platen sheet from the securing lugs 388.

Although the blanket has been shown diagrammatically as secured in a relatively permanent manner, it is desirable that it also be stretched, and it may be readily removable, if desired, so as to facilitate replacing it with a harder blanket for direct letter-press printing.

OPERATION

The general operation is sufficiently clear from the description of the general organization at the beginning of this specification. The operation of the various parts is sufficiently clear from the description of each of said parts. The timed relationship of the various parts is most clearly shown in Fig. 12A.

It is believed that for the most part the chart in Fig. 12A will be sufficiently clear without explanation. The zero position is approximately

the time at which the plate J reaches the bite between the cylinders I and M, which happens also to be shortly before a sheet is initially picked up by the sheet separator C. Line 1 of the chart shows what part of the surface of the main cylinder I is at the position of the bite at each angular position of the cylinder I, represented by the vertical lines on the chart. This line 1 therefore serves very conveniently as a reference line from which to compare the position of the main cylinder I and the other parts.

Line 2 of the chart indicates the movement of a sheet of paper from the time it is picked up until it is released. It will be observed that this complete movement takes over two cycles of the press, and hence the upper run of this line shows the position of the last sheet, while the second run of this line shows the position of an advanced or first sheet for any given angular position of the cylinder I.

Lines 3, 4, and 5 show the operation of the various illustrated parts of the registration feeding unit.

Line 6 illustrates the operation of the feeler finger 113, and indicia thereon indicates the operation of the counter operated thereby when a sheet is present and the trip finger operated thereby when no sheet is present.

Line 7 is a composite line illustrating in its upper line the position of the small cylinder M when sheets are being fed continuously, and in its lower line the position of the small cylinder M when sheets are missing continuously. The period when the two lines coincide is the period which corresponds to the highest portion of cam 137 which, when a sheet has just been printed, relieves the pressure of disc 99 on latch arm or pawl 101, so that if the trip finger 121 has been actuated, as in line 7, the latch arm 101 may drop. If the latch drops, the small cylinder will follow the lower line for the next cycle, and, if not, it will follow the upper line.

Lines 8 and 9, respectively, show the action of the form rollers, line 8 illustrating the action of one ink form roller, and line 9 illustrating the action of the water form roller. In each instance the raised portion of the line represents the period during which the roller is raised by the cams 227, during offset printing.

Line 10 illustrates the operation of the gripper fingers on the chain-carried gripper unit Q. A more natural zero point for the cycle of these gripper units would be at approximately the line corresponding to the 120° position of the chart. Following this it is seen that the gripper opens to receive the sheet, and then closes upon the sheet. The dotted-line hump in the curve thereafter represents the opening of the grippers to release the sheet, if the sheet is being printed by direct printing on its upper face. If the cam V is moved to its idle position, the gripper will not open at the position indicated by the dotted-line portion of line 10 on the chart, but will be opened by cam R after it has turned the sheet over.

65 I claim:

1. A printing press including a printing couple, one member of which is a cylinder bearing image-forming means, said cylinder including discs rotating in timed relationship to the other member 70 of the couple, and a cylindrical segment carried by the discs and bearing the image-forming means on the outer surface thereof, said segment being circumferentially adjustable with respect to the discs to adjust the head margin of a sheet being printed.

2. A printing press including a printing couple, one member of which is a cylinder bearing image-forming means, said cylinder including discs rotating in timed relationship to the other member of the couple, and a cylindrical segment carried by the discs and bearing the image-forming means on the outer surface thereof, said segment and a disc comprising members which are relatively circumferentially adjustable to adjust the head margin of a sheet being printed, and one 10 of said relatively adjustable members being provided with calibrations visible adjacent a reference indication on the other of said members to facilitate adjusting the segment to a desired position.

3. A printing press including a printing couple, one member of which is a cylinder bearing image-forming means, said cylinder including discs rotating in timed relationship to the other member of the couple, and a cylindrical segment carried by the discs and bearing the image-forming means on the outer surface thereof, said segment being circumferentially adjustable with respect to the discs to adjust the head margin of a sheet being printed, said discs being adapted and constructed for securing a second segment at a position generally diametrically opposite the first segment and with like circumferential adjustability.

4. A printing press including a printing couple, one member of which is a cylinder bearing image-forming means, said cylinder including discs rotating in timed relationship to the other member of the couple, a cylindrical segment carried by the discs and bearing the image-forming means on the outer surface thereof, said segment being circumferentially adjustable with respect to the discs to adjust the head margin of a sheet being printed, means for locking the segment against movement, and means for turning the discs by hand while the segment is thus locked.

5. A printing press including a printing couple, one member of which is a cylinder bearing image-forming means, said cylinder including discs rotating in timed relationship to the other member of the couple, and a cylindrical segment carried by the discs and bearing the image-forming means on the outer surface thereof, said segment being circumferentially adjustable with respect to the discs to adjust the head margin of a sheet being printed, and means for thus adjustably securing the segment to the discs comprising a nut for each disc having a cylindrical surface bearing outwardly on a cylindrical surface of said disc, said disc being shaped to prevent rotation of the nut about the axis of the nut while permitting its adjusting movement about the axis of the disc, and a screw extending through the segment for engaging said nut.

6. A printing press including a printing couple, one member of which is a cylinder bearing image-forming means, said cylinder including discs rotating in timed relationship to the other member of the couple, a cylindrical segment carried by the discs and bearing the image-forming means on the outer surface thereof, said segment being circumferentially adjustable with respect to the discs to adjust the head margin of a sheet being printed, and means for thus adjustably securing the segment to the discs comprising a nut for each disc having a cylindrical surface bearing outwardly on a cylindrical surface of said disc, said disc being shaped to prevent rotation of the nut about the axis of the nut while permitting its adjustment movement about the axis of the

disc, a screw extending through the segment for engaging said nut, and means for holding each said nut in position while the segment is removed.

5 7. A dampening unit for a printing press, including a frame, a fountain, a fountain roll, a ratchet wheel for driving the fountain roll, a pawl and a cam follower lever for actuating the pawl, a ductor roll and a cam follower lever for oscillating the ductor roll, cam means for driving the cam follower levers, a distributor roll, a form roller, and a pinion for driving the cam means, distributor roll and form roller, all carried by the dampening unit frame, said frame being removable attachable to a printing press frame and, upon attachment, automatically positioning the pinion in proper position to be actuated by corresponding parts of the press.

8. A dampening unit for a printing press, including a frame, a fountain, a fountain roll, a ratchet wheel for driving the fountain roll, a pawl and a cam follower lever for actuating the pawl, a ductor roll and a cam follower lever for oscillating the ductor roll, cam means for driving the cam follower levers, a distributor roll, a form roller, and a pinion for driving the cam means, distributor roll and form roller, all carried by the dampening unit frame, said frame being removable attachable to a printing press frame and, upon attachment, automatically positioning the pinion in proper position to be actuated by corresponding parts of the press; said positioning being determined by a slip-on connection between the frames pivotal about an axis spaced from the follower and pinion and an adjustable spacer between the frames remote from said axis.

20 9. A two-purpose printing press including a larger cylinder, a smaller lower cylinder, and inking and dampening units at times accessibly positioned adjacent the top of the upper cylinder and cooperating therewith; said dampening unit being readily removable, and said larger cylinder including a segment readily removable after removal of the dampening unit for replacement by a different form of segment.

10. A two-purpose printing press including two cylinders by which a sheet is printed, one of said cylinders including a transfer surface and cooperating with a plate for receiving an image from the plate and applying it to one face of the sheet for offset printing, the other of said cylinders normally including a platen surface for the sheet in offset printing but at times including printing means adapted to print the face 25 of the sheet opposite from that which would be printed with offset printing, feeding and registration means for feeding sheets to the bite between said cylinders including side guide means, means for urging the sheet in either lateral direction against the side guide means for lateral registration of the sheet, and means for engaging the leading edge of the sheet to obtain longitudinal registration, and means for delivering the sheet either-side-up after it has been printed whereby 30 with either type of printing a given side edge of the sheet may be used for registration and the printing may be exposed on the delivery pile for inspection.

11. A two-purpose printing press including two cylinders by which a sheet is printed, one of said cylinders including a transfer surface and cooperating with a plate for receiving an image from the plate and applying it to one face of the sheet for offset printing, the other 35 of said cylinders normally including a platen

surface for the sheet in offset printing but at times including printing means adapted to print the face of the sheet opposite from that which would be printed with offset printing, and feeding and registration means for feeding sheets to the bite between said cylinders including side guide means, means for urging the sheet in either lateral direction against the side guide means for lateral registration of the sheet, and means for engaging the leading edge of the sheet to obtain longitudinal registration whereby a sheet may be registered by the top and a given side of the sheet no matter which side of the sheet is up.

12. A dampening unit for a printing press, including a dampening unit frame, a fountain, a

5 fountain roll, a ductor roll, cam means for driving the cam follower levers, a distributor roll, a form roller, and a pinion for driving the fountain roll, ductor roll, distributor roll and form roller in timed relationship, all carried by the dampening unit frame, said dampening unit frame being removably attachable to a printing press frame and, upon attachment, automatically positioning the pinion in proper position to be actuated by a gear of the press; said positioning being determined by a slip-on connection between the frames pivotal about an axis spaced from the pinion and an adjustable spacer between the frames remote from said axis.

WILLIAM WARD DAVIDSON.
